United States Patent Office

Des. 217,856

Patented June 23, 1970

217,856

RESTAURANT BUILDING FRONT EXTERIOR

Albert J. Miller, San Jose, Calif., assignor to Cable Car Burgers, Inc., Oakland, Calif., a corporation of Colorado

Filed June 9, 1969, Ser. No. 17,607

Term of patent 14 years

Int. Cl. D25—01

U.S. Cl. D13—1

Fig. 1

Fig. 2

FIG. 1 is a front perspective view of a restaurant building front exterior showing my new design; and

FIG. 2 is a side elevational view thereof.

I claim:

The ornamental design for a restaurant building front exterior, substantially as shown and described.
